PLANT-MANUFACTURED BUILDING STRUCTURE
John H. Slayter, Newark, Ohio, assignor to Richardson
Homes Corporation, a corporation of Indiana
Filed Mar. 1, 1963, Ser. No. 262,148
7 Claims. (Cl. 52—73)

This application is a continuation-in-part of copending application Serial No. 160,984, filed December 21, 1961, which issued as Patent No. 3,156,018 on November 10, 1964.

This invention relates to a Plant-Manufactured Building Structure. It has to do, more particularly, with a modular or segmentized building structure formed of pre-built cooperating assembled transverse sections or modules, with the structure of the assembled transverse sections or modules to be used in such a building structure, and with the prebuilt transverse trusses used in the formation of such building sections. It also relates to novel details of structure incorporated in the trusses, building sections, and the completely assembled building structure.

In general, this invention like the one disclosed in said patent embodies a modular building structure made up of a plurality of transverse modules or sections which can be disposed in cooperative relationship, drawn together and clamped together with weathertight joints between the modules or sections. The modules or sections rest upon and are supported upon a plurality of longitudinally extending main supporting beams upon which they slide when drawn into cooperative clamped relationship as indicated above. Each of the sections or modules includes a plurality of basic truss units which extend transversely of the sections and which are structurally connected together. According to this present invention, each of these basic truss units is a composite unit which includes a pair of supporting outer or side columns, a pair of inwardly extending cantilever type truss arms which serve to support the roof deck, and which may support ceiling panels, which meet midway of the columns, and a floor joist beam or truss portion which is connected to the lower ends of the columns. All connections between floor joist, columns and roof truss arms are of the rigid type. Thus, the composite truss unit of this invention is a continuous, closed framework, wherein the frame members are disposed in angular relationship with their adjacent ends rigidly connected together and are free of any angular bracing or struts thereby making it possible to provide standard or common transverse sectional contours in the building sections or modules manufactured therewith as compared to the unusual transverse sectional contours of modules constructed with the trusses of my said patent which follow the moment curves and include necessary bracing and struts. This arrangement according to the present invention is such that the roof loads cause the cantilever arms to act not only in compression but applies a bending force, which in turn creates a moment which is transmitted through the rigid connections to the side wall columns and in turn to the floor joists. The floor joist is loaded, therefore, not only in tension by this transmitted load but is in turn subjected to an upward bending moment that is exactly reverse to the downward bending moment created by static floor loading. Each floor joist rests on the main supporting beams, preferably two parallel beams, and the entire composite truss unit is supported thereby. The floor joist or truss portion rests on the beams in such a manner that there is a projecting overhang outwardly of the respective beams. Therefore, roof loads acting on the cantilever truss arms and floor loads acting on the joist beams tend to create opposing bending moments in the plane of the truss unit which result in a type of structural loading known as "reverse bending," the favorable result of

which is the decided decrease in structure deflection at the same static loading than would be possible if the floor truss were supported at its outer ends or if the structure joints were not rigidly connected. Also, according to this present invention, all wall structures, partitions, etc. are so designed and connected with the truss units by slip joints so as to permit flexing of the truss units without any damage to the wall structures. The truss units can, therefore, be of metal, such as steel, and need not be sufficiently heavy to be rigid but can be of relatively light construction even though they have considerable flexibility. Also, the relative flexing between the truss units and associated walls will take care of the difference in contraction and expansion of the trusses as compared with the wall structures which are of different materials.

In the accompanying drawings, one embodiment of this building structure and examples of units and structures used therein are illustrated, but it is to be understood that details of all these structures may be varied as to appearance and materials without departing from basic principles of my invention.

In these drawings:

FIGURE 33 is a view similar to FIGURE 32 but showing a cap used at the joints between roof panels.

FIGURE 34 is a vertical sectional view taken along line 34-34 of FIGURE 33.

FIGURE 35 is a vertical sectional view of another form of connector for connecting adjacent trusses of adjacent building sections.

FIGURE 36 is a horizontal sectional view taken along lines 36-36 of FIGURE 35.

FIGURE 37 is a vertical sectional view similar to FIGURE 14 but illustrating how a nailing strip can be used on the roof truss arms of the metal truss.

FIGURE 38 is a sectional view illustrating the use of nailing strips on the side column and also illustrating somewhat different associated wall structures.

FIGURE 39 is a vertical sectional view showing a different arrangement of the roof truss arm structure of associated trusses.

FIGURE 40 is a perspective view of a building section mounted on a trailer for transport.

With reference to the drawings, there is illustrated generally in FIGURE 1 a building structure embodying principles and structure of this invention. The building structure shown is of the type used as a house or residence but it is to be understood that this is merely one example of a building which can be built according to this invention. The illustrated building structure consists of a plurality of transverse modules or sections which are identical in basic structure but which may vary from each other in exterior design and finish and in interior design and finish. Also, the interiors of the various sections may have built-in equipment which varies from section to section. For example, usually one of the sections is a utility core

or section which will contain kitchen, bathroom and heating and/or air conditioning equipment. This section may be located relative to the other sections as desired. Other sections may have living room furniture built in and still other sections may have bedroom furniture built in. Thus, there may be wide variation in regard to the relationship and to the equipment of the various sections.

In the example illustrated, the house is shown as consisting of a plurality of main transverse modules or sections 41 and 42 and a pair of transverse terminal or end sections 43, but it is obvious that the number of main sections could be varied. Each of the end sections 43 forming a building structure, although similar in structure to the main sections 41 and 42, are provided with end walls 44, as best shown in FIGURE 1. The specific structure of the end wall will be more fully explained herein-after. The supporting framework members of the sections are designed primarily to be fabricated from light-weight structural steel shapes. Wall, roof and floor sheathings or coverings which may be fabricated or formed from various well-known building materials such as wood, synthetic substances or metals, or any combination thereof, are secured to the respective elements of the framework to resist racking or twisting of the building structure without the addition of the conventional diagonal bracing members. Weathertight seals are formed between the several sections or modules when joined together, either by the compressive force exerted between adjacent sections holding opposed edge portions in contacting engagement, the particular arrangement of the sheathing or external covering members, or by additional sealing members that are readily attachable to the structure itself. The support for the entire building is shown as consisting of the pair of longitudinally extending, main supporting beams 45 and 46 which are disposed in parallel relationship. Additional details as to the structure of the beams 45 and 46 as well as connection with the building structure and foundation members will be described in subsequent paragraphs.

Each transverse section or module is constructed with a plurality of basic truss units, indicated generally by the numeral 47, which form the structural framework thereof. A complete truss unit 47 is illustrated in FIGURE 2 and includes a floor joist 48, a pair of side columns 49 secured to the outer ends of the joist, and a pair of inwardly extending, cantilever-type roof truss arms 50 attached to the upper ends of the side columns. In the present embodiment, the floor joist 48, as well as the cantilever roof truss arms 50, are fabricated from two or more beam sections. The several beam sections are rigidly connected to each other in an end-to-end relationship to form a beam or truss of the desired length. The utilization of relatively short beam sections is primarily an economic factor as it reduces the cost of manufacture of the building and it is readily apparent that a unitary beam of the required length may be utilized. To further reduce the cost of manufacture, each member of a truss unit 47 is fabricated from a C-shaped channel beam of the general form shown in FIGURE 4 including web and flange portions with each of the flange portions having the marginal edge thereof turned inwardly forming a flange lip disposed parallel to the web portion. This particular shape of channel permits the flange and web portions thereof to be rolled or otherwise formed from a relatively thin sheet of material while retaining the strength of a heavier beam. The weight of each truss unit is also minimized for a predetermined load-carrying capacity which results in a reduction of the total weight of a complete building.

To obtain the desired structural characteristics, all members of each truss unit must be securely and rigidly secured together. When thus fabricated, the several members form a composite truss unit that is relatively rigid and is capable of supporting the predetermined design loads within allowable limits of flexure. This

limiting of deflection is accomplished through the phenomenon known as reverse bending, which is created in all members concerned by virtue of the rigidly connected joints and the supporting of the floor members at a point other than at the extreme ends. Were either of these essential requirements eliminated, the reverse bending phenomenon would not be achieved and much stiffer and consequently heavier steel sections would be required to achieve the same deflection limits. Increasing or decreasing the load on each truss unit will cause the truss unit to flex in a vertical plane. FIGURES 3 through 9a illustrate the various methods of obtaining rigid joints between the several members of the truss unit.

FIGURE 3 is an enlarged detail of the connection between the roof truss arms 50 at the center of the building or the roof ridge. The adjacent ends of the truss arms 50 are angularly cut and shaped to fit in an end-contacting relationship to form a sloped roof and are subsequently welded together. Additional stiffening or reinforcing of the truss arms 50 at the ridge is provided by the insertion of a flat plate 51 into the channel of each arm at the adjacent ends thereof. The plates 51 are welded to the truss arms 50, as indicated in FIGURE 4, along the edges in contact with the flange and web portions.

A typical rigid joint between a roof truss arm 50 and a side column 49 is illustrated in FIGURES 5 and 6. A cap plate 52 is first welded to the upper marginal end of the side column 49 and the roof truss arm 50 is then set on the cap plate and welded thereto. The upper end of the column 49 is accordingly angularly cut in conformity with the slope of the roof truss. A pair of flanged reinforcing members 53 are also positioned within the roof truss arm 50 at the marginal end thereof adjacent the side column 49. The flanged reinforcing members 53 form continuations of the flanges of the side column 49 and are welded rigidly in position with the flanges thereof aligned with and parallel to the flange lips of the truss arms 50. An extremely rigid, lightweight joint is thus formed with the truss members being reinforced as to racking or twisting forces. The roof truss arms 50 do not extend outwardly from the side columns 49 to form a supporting structure for the eaves as in conventional constructions and, as will be subsequently explained, the eaves are integrally formed with the roof sheathing in a novel and economically fabricated construction.

Each side column 49 is also rigidly secured to the extreme end of a floor joist beam 48 and the details of this joint are clearly illustrated in FIGURES 7 and 8. Welded to the extreme end of the floor joist is an end cap 54 and a reinforcing plate 55 is welded to each of the flange portions thereof to provide sufficient strength at the marginal end of the joist. The side column 49 is then welded to the end cap 54 and the reinforcing plates 55. An additional pair of reinforcing plates 56 are welded in the interior of the side column 49 in spaced, parallel relationship forming continuations of the flanges of the floor joist beam 48 to increase the resistance of the column to racking or twisting forces.

The method of joining or splicing two of the relatively short beams from which the long members of a truss unit 47 are fabricated, such as a truss arm 50, is illustrated in FIGURES 9 and 9a. The two beams are placed in end-contacting relationship and a spline 57 fabricated from a similarly formed but proportionally smaller sized C-shaped channel is inserted within the channel of the beam. The relatively short spline 57 extends a distance to each side of the joint and is rigidly fastened to the beams, by welding, for example. The joint between the two beams is also welded together.

The complete truss unit 47 thus formed is a substantially rigid structure capable of supporting the static and dynamic loads for which it was designed. These design forces include the dead weight of the building materials and the normal furniture loads and also wind, snow, or other natural forces. The truss units 47 are disposed in a

generally vertical plane extending transversely of the longitudinal beams 45 and 46 and are preferably positioned thereon in such a manner that the floor joist beam 48 will be supported intermediate the ends thereof, as best shown in FIGURE 2. The position of the beams 45 and 46 relative to the floor joist beam 48 is determined by design requirements of the specific structural beam section to minimize deflection as well as stress through the achievement of reverse bending in the floor beam section. Although the stress in the floor joist 48 is substantially reduced by the preferred location of the supporting beams 45 and 46, it may be necessary to increase the size of the floor joist 48 relative to the side columns 49 and the roof truss arms 50 to provide a truss unit 47 capable of supporting the maximum design load.

Each transverse section or module is fabricated from a plurality of the basic truss units 47 disposed in spaced parallel relationship. A completed module, such as 41 or 42, is shown in FIGURE 40 and a partially constructed end module 43 is illustrated in FIGURE 10 on an enlarged scale to clearly indicate the method of construction. The truss units 47 are uniformly spaced in standard units, such as 4 ft., and each module may be of a length such as 8 or 12 ft. which are a multiple of the basic spacing. The module illustrated in FIGURE 40 is of the 12 ft. width and utilizes six of the truss units. A single truss unit 47 is disposed at each of the transverse edges of the module with the channel opening inwardly thereof. Thus, only the web portions of the channel members of the end trusses will be visible in a completely assembled module. The remaining four trusses 47 are disposed in pairs intermediate the end trusses in which the web portions of two adjacent truss units are in contacting engagement. The positioning of the truss units in pairs is clearly shown in FIGURE 10. The transverse edges of each module adapted to be positioned centrally of a building structure are only provided with one truss unit 47 as the module positioned adjacent thereto will provide the additional truss unit. When the two modules are positioned in assembled relationship, the adjacent end truss units will also be positioned with the web portion thereof in contacting engagement. Each module will, therefore, be a self-contained, self-supporting building unit which may be readily combined with other modules of the same basic form. The interior arrangement of the modules is completely independent of the module as the truss units are self-supporting and do not require additional support members to be positioned between the floor joist and roof truss arms.

Although each of the truss units 47 is formed as a substantially rigid truss member, the truss units are designed to flex in a vertical plane when subjected to various loads. This type of design permits the utilization of lighter weight beam members for economic and weight advantages. As an example, when a truss unit 47 is subjected to its proportionate share of a static load, a uniform floor and roof load, for example, the floor joists 48 will be flexed downwardly at the outer ends thereof while the center portion will also be flexed downwardly. Simultaneously, the roof truss arms 50 will be subjected to bending stresses which results in a downward movement of the roof truss arms 50. The downward movement of the roof truss arms is further increased by the downward flexing of the floor joists 48. Preferably, the floor joists 48 are designed to have substantially less flexing when subjected to a maximum design load than are the roof trusses 50. This may be readily accomplished by utilizing a substantially larger member for the floor joist 48 as was previously suggested. When the roof truss arms 50 are subjected to a substantially uniform roof loading, the truss arms will be flexed downwardly as well as lowered. The relatively larger movement of the roof truss arms 50 compared to the floor joist beam 48 is not of particular importance except for the general appearance of the building structure. It is generally immaterial to the oc-

cupant that the roof truss 50 is flexed downwardly unless overhead clearances should be decreased beyond a reasonable limit. However, extreme flexing of the floor joists 48 is undesirable and will be readily noticeable in the location and operation of appliances, as well as the appearance of other furniture items. Simultaneously with the flexing of the roof truss arms 50 and the floor joists 48 in a vertical plane, the side columns 49 will be observed to become inclined relative to their normal vertical position but the inclination is relatively small compared to the roof. By virtue of all rigidly connected joints, a static roof load results in a bending moment which is transmitted through the rigid joint between each roof truss arm 50 and the side column 49 and then through the rigid joint between it and the floor joist 48 to the floor joist itself. This transmitted moment opposes the moment created by the static loading of the floor joist itself, thus creating the structural phenomenon known as reverse bending. The analysis works equally as well in reverse with bending moments created by the static loading of the floor being transmitted the other direction equal and opposite through the side columns 49 to the roof truss arms 50, these moments being opposite to the moments created by the static loading of the roof. The result is that all members of the rigid structure are subjected to reverse bending conditions which allows them to assume much greater loads with less flexing or deflection than would be possible if the reverse bending phenomenon were not achieved. Two factors are absolutely essential to achieve this phenomenon. One is the rigidly connected joints of all members, and the second is the support of the entire trusses unit at a mathematically predetermined point a distance inward from the ends of the floor joist 48.

To quantitatively illustrate the magnitude of the flexing movement referred to herein, a test model comprising a plurality of the truss units 47 was constructed and subjected to various load conditions. For one particular test condition, maximum design load, the floor joists 48 were subjected to a uniform loading of 65 pounds per square foot on an effective two ft. wide module. Simultaneously, the roof truss arms were subjected to a uniform loading of 24 pounds per square foot. In this test model, the floor joists 48 were fabricated in the form of C-shaped channels having a web of 8 inches and a flange of 3 inches from 10-gauge flat stock structural steel having a 33,000 p.s.i. yield point. The joists were 30 ft. in length. The roof truss arms 50 were similarly fabricated but from 12-gauge flat stock structural steel having a 50,000 p.s.i. yield point. The dimensions of the roof trusses were 6 inches for the web and 2½ inches for the flanges. The deflections noted in this test were that the floor joists 48 were flexed downwardly at the extreme ends thereof approximately ½ inch while the center portion of the floor beam was only flexed downwardly ¼ inch. The total downward movement of the roof truss arms 50 during this test was ascertained to be a maximum of 1⅓ inches at the ridge thereof with the deflection of each arm decreasing toward the outer ends thereof connected to the side columns 49. Simultaneously, the upper ends of the side columns 49 were observed to have moved approximately ¼ inch horizontally outward from their normal position. It was noted that the deflection of the roof truss arms 50 relative to the floor joists 48 was extremely variable over the entire length of the truss unit with the maximum variation in deflection occurring at the center or roof ridge of the truss and decreasing to a minimum at the marginal ends thereof adjacent the side columns 49.

It is obvious the other test loads or loadings of a test model would result in variations of the deflections previously indicated. As an example, with non-uniform loadings it is possible to produce an upwardly directed deflection in the roof truss arms 50 as well as the outer ends of the floor joist beams 48. An example of such a deflection

was observed when the roof truss arms 50 were subjected to a substantially less than normal loading as were the portions of the floor joists 48 extending outwardly from the respective support points. The center span of the floor joist 48, however, was subjected to the normal loading and was, therefore, the only portion of the truss unit experiencing a downward deflection.

Each of the modules includes several sheathing members as part of the structure which must necessarily be designed to accommodate the vertical flexing movement when subjected to variations of load. A suitable sheathing material is applied to the floor joists 48, the side columns 49 and the roof truss arms 50 to provide resistance to racking or twisting forces. The sheathing on the respective members of the truss units 47 must be of a type which will not be affected by a vertical flexing movement of the truss and will readily accommodate any bending that may occur in the associated truss member. The sheathing applied to the respective members of the truss units must be fabricated from suitable materials having the desired strength characteristics to resist racking. Also, it is necessary that all interior walls or partitions be movable relative to the truss units 47 and associated sheathings to prevent damage to the structures during flexure of the truss units. Since the truss units 47 are structurally self-supporting and are of the open-span type, the various interior walls may be of the free-standing or curtain-wall type which are not usually subjected to any vertical loadings.

The basic structure and constructional characteristics of a module and an end wall 44 are illustrated in FIGURE 10. The module illustrated is an end module 43; however, the essential constructional characteristics would apply to either of the modules 41 and 42 adapted to be positioned centrally of the building structure. In FIGURE 10, two truss units, indicated herein as trusses 47a and 47b for purposes of differentiation, are longitudinally disposed on the supporting beams 45 and 46 at the desired basic module spacing of four feet. A floor sheathing member 60 is then applied to the upper flange of the floor joist 48 as are sheathing members 61 and 62 to the exterior and interior flanges of the side columns 49 and a roof sheathing, denoted generally by the numeral 63, to the upper flanges of the roof truss arms 50. The various sheathings are rigidly secured to the respective truss members by any suitable fastening means such as self-tapping sheet metal screws or power driven screw nails. The spacing of the fastening means is determined by the type of material utilized and the particular fasteners. Utilization of sheet metal material in the fabrication of the truss units permits the use of fasteners of this type which are readily applied by powered apparatus and equipment thus effecting a reduction in fabrication costs. A module is further built up by the addition of other pairs of truss units 47 to obtain a readily transportable unit having a width of eight or twelve feet. As indicated, the next truss unit 47c is positioned adjacent the truss unit 47a with the web portions thereof in contacting engagement. The truss units 47a and 47c are then rigidly secured together by suitable fastening means such as bolts 64. A plurality of bolts 64 are utilized substantially as indicated in FIGURE 2. Preferably, the truss units are first assembled in pairs, such as 47a and 47b, with the sheathing secured thereto for economic assembly operations and thus form module subsections. Such a subsection will thus be fabricated from standard length parts that are readily produced under mass manufacturing methods. A subsection of four-foot width is also readily transferrable throughout a factory assembly plant. Although the sheathing may be applied to the subsection before assembly, there will be no difficulty encountered in fastening the subsections together as the bolts are applied only to the portions of the trusses which are readily accessible.

An end module 43 includes a vertically disposed wall 44 and an overhanging roof portion or eave member.

The overhanging roof portion is preferably formed as a continuation or extension of the roof sheathing 63 applied to the end module 43 while the vertical wall 44 must be supported for movement relative to the associated truss units 47. The details of the construction of an end wall 44 and a roof overhang and the attachment thereof to the end module 43 is best illustrated in the FIGURES 10, 12, 13, 14, and 16. As indicated in the several figures, the end wall 44 is fabricated as a structurally rigid unit which must be vertically supported at the transverse edge of the end module 43. The roof overhang, although integrally formed with the roof sheathing 63 carried by the end module 43, represents additional weight that may excessively load the truss unit 47b disposed at the transverse edge of the module. Therefore, a truss unit 47d is disposed in a vertical plane adjacent to the truss unit 47b to support the wall 44 and carry the weight of the roof overhang. However, the web portions thereof are not in contacting engagement as are the adjacent pairs of truss units such as 47a and 47c. A spacing member 65 is positioned between the webs of the adjacent channel members 47b and 47d which is of a thickness equal to the desired spacing between the trusses. The spacing member 65 may be an elongated strip of wood or similar noncompressible material extending around the periphery of the truss units adjacent the outer flanges thereof or a plurality of relatively short blocks. In addition, a washer 64a of the same thickness is positioned on each of the bolts 64 fastening the truss units 47b and 47d together so that the web portions will be maintained in parallel relationship. The web portions of the respective truss units 47b and 47d will form a slot or channel opening inwardly of the truss units and extending substantially around the periphery of the truss units.

The floor sheathing 60, which is secured to the upper flange of the truss unit 47b by any suitable fastening means such as screw nails 66, is formed from panels of structural materials capable of supporting the loads placed thereon as well as resisting the racking forces to which the structure may be subjected. The panels may be fabricated from $\frac{3}{4}$ inch thick plywood. An insulation sheathing 67 may also be applied to the lower flanges of the floor joists 48 to thermally insulate the floor of the building. The insulation sheathing 67 is formed in panels which are secured to the truss unit 47b by screw nails 68. Any of the well-known rigid sheet insulation panels which are resistant to moisture may be utilized. It is readily apparent that other forms of insulation may also be utilized, such as replacing the insulation panels 67 with a skin member formed from metal, for example, and filling the space between the floor sheathing 60 and the skin member with a granular or nonrigid battting type of insulating material. The floor sheathing 60 and insulation panels 67 terminate at the web portion of the truss units and, in the case of the end modules, do not extend over the space between the truss units 47b and 47d.

The end wall 44 is fabricated as a rigid, self-supporting unit similar to the conventional structural walls having a plurality of vertically disposed studs 70 which are attached to a horizontally extending sole plate 71. Openings 72 and 73 may be integrally framed in the wall stud 70 to receive windows as desired. Additional openings of proper form may be provided for installation of doors. The sole plate 71 is supported on the upper flange of the floor joist of the truss unit 47d which truss unit will, therefore, support the entire end wall 44. The sole plate 71, however, is not rigidly secured to the truss unit 47d except at points immediately above the longitudinal beams 45 and 46. The end wall 44 is of substantially rigid construction and will, therefore, be incapable of flexing in a vertical plane, as is the truss unit 47d on which it is supported. Since the floor joist 48 of this truss is also rigidly supported at the longitudinal beams 45 and 46, there will be no relative movement of the sole plate 71 and the truss at this point thus eliminating the necessity

of a movable or slip joint at this location. Any suitable fastening means may be utilized, such as a bolt 74, extending through the upper flange of the truss unit 47d and the sole plate 71, as indicated in FIGURE 16.

It is necessary that the remaining marginal edge portions of the end wall 44 be connected by means of slip joints to the truss unit 47d and the sheathing members attached thereto to permit relative movement. An interior wall sheathing 75 is applied to the vertical studding members 70 to form an interior wall surface. The sheathing 75 may be formed from sheets of suitable building materials, such as plywood or composition wood having a plastic surface, and is fastened to the studs 70 by a suitable fastening means, such as nails. The sheathing 75 is cut to such a length that the marginal edge portions thereof will extend a distance beyond the framing members 70 and 71 into channels formed by adjacently disposed portions of the truss units 47b and 47d, as illustrated in FIGURES 12, 14 and 16. The spacing between the truss units 47b and 47d is determined by the thickness of the sheathing 75 and must be adequate to permit relatively free sliding movement of the sheathing therebetween. The end walls may, therefore, move relative to the truss units without adverse distorting effects. It is readily apparent that the sheathing 75 will also serve to maintain the wall member 44 in a vertically upright position. An exterior sheathing 77 may also be applied to the vertical studs 70 in a similar manner. The exterior sheathing 77 is preferably formed from an insulating material consisting of rigid sheets to which a protective and decorative siding 77a such as the clapboard type may be applied. The sheathing 77 extends downwardly from the sole plate 71 to at least an overlapping relationship with the bottom sheathing 67 to enclose the truss units and provide a weather-proof seal. A spacing member 78 of L-shaped cross section may be fastened to the lower flange of the truss unit 47d, as illustrated in FIGURE 16, to provide an additional bearing surface for movement of the wall member 44 and to aid in maintaining the wall in a vertical position. The spacing member 78 is not secured to the sheathing 77. A similar spacing member 78a is secured to the lower flange of the roof truss arm 50 of the truss unit 47d. A closure member 79 may then be secured to the exterior of the flange of truss unit 47d to completely seal the wall member 44. The closure member 79 would be fastened to the flange of the truss unit 47d by suitable means such as metal screws after the truss unit fastening bolts 64 have been installed.

An elongated strip of interior molding or trim 76, such as a quarter-round, may be nailed to the floor sheathing 60 adjacent the sheathing 75 to provide a more finished appearance and to eliminate the necessity of accurately cutting a smooth abutting joint along the marginal edge of the floor sheathing 60. It is to be understood that other floor surfacing or covering materials may be applied to the upper surface of the floor sheathing 60 to improve the appearance thereof. For example, hardwood flooring or composition tiles may be laid over the sheathing. In that instance, the quarter-round 76 would be disposed above the floor covering. With certain types of floor coverings, at the floor joints between adjacent building sections or modules it may be desirable to have corresponding joints in the floor covering with trim strips over the joints.

The slip joint structure of the end wall 44 with the longitudinal side walls of the building structure is best illustrated in FIGURES 12 and 13. The interior and exterior wall sheathing members 62 and 61 are applied to the interior and exterior flanges of the side column members 49 and fastened thereto by any suitable means, such as sheet metal screws or bolts. A plurality of side column spacer blocks or single elongated spacing members 80, similar in form and operation as the spacer blocks 78, 78a described in conjunction with the floor joist and roof truss arms, are fastened to the exterior

flange of the end truss unit 47d. An extension 81 of the exterior sheathing 61 is also fastened to the side column of the end truss 47d forming an edge cover for the end wall 44. The extension 81 may be formed integrally with the wall siding 62. A protective and decorative clapboard siding 82 is also applied to the sheathing 62. Before securely fastening the clapboard siding 82 to either the side wall or the end wall, a preformed metal corner member 83 is fastened to the sheathing extension 21 to form a decorative and weathertight seal at the junction of the side and end wall members and permit movement of the end wall relative to the side wall. The corner member 83 (see FIGURE 13) is formed from a sheet metal with a pair of vertically extending channels 84 for receiving the clapboard siding and a pair of flange members disposed in contacting engagement with the respective wall sheathing 81 and 77. To permit relative movement of the end wall 44, the corner member 83 is only fastened to the sheathing extension 81. Thus, the clapboard siding applied to the end wall 44 may not only slide transversely relative to the corner member 83 but longitudinally thereof, along the clapboard receiving channels 84.

FIGURES 10, 14 and 15 illustrate the structure of the roof sheathing 63 and the construction of the roof overhang at the end walls and the longitudinal side walls. The roof sheathing 63 includes a substantially rigid sheet or panel 85 formed from a suitable material such as plywood, which may be readily fastened to the truss units 47 by metal screws or power-driven screw nails. The plywood panel 85 must be capable of resisting racking or twisting forces to which the building structure may be subjected. Also, the panel 85 may extend outwardly from the end wall members, as shown in FIGURE 14, or the longitudinal side walls, as shown in FIGURE 15, to form the structural member of the roof overhang or eave. A panel of insulation 86 of the type which may be fabricated in sheet form is placed over the roof sheathing 85. An external, protective metal skin or panel 87 is then placed over the top of the roof insulation and maintained in its proper position.

The roof sheathing 63 is formed in elongated sheets as shown in FIGURE 10 which extend transversely of the section module. The roof sheathing panels are maintained in their respective positions by means of roof batten structures or seam caps 88. The roof batten structures 88 extend transversely of the building structure and are preferably positioned at the truss units 47. Each of the batten structures 88 includes one or more elongated bars 89 which are secured to the plywood panel 85 by means of a plurality of wood screws 90 or nails. The screw 90 extends through the batten and into the panel 85. The sides of the bar 89 are inclined upwardly and outwardly from the panel 85 forming a wedge structure to engage the insulation panels 86 and the roof skins 87 to retain them in an overlying relationship to the roof sheathing 85. For this purpose, the roof insulation panels 86 are preformed to have an inclined edge portion which cooperatively engages the inclined side of the bars 89. The roof skins 87, which are preferably fabricated from a sheet metal such as aluminum, are formed with a flanged edge portion which also engages the inclined side of the bar 89. The flanged edge portion includes a flange 91 inclined upwardly and outwardly similar to the inclined surface of the bar 89 and which terminates in a lip member 92. The lip member 92 is disposed in a plane parallel to the main body of the panel 87 in overlying relationship thereto. The roof sheathing panels 86 and 87 will thus be maintained in position by the roof batten structures 88 without requiring the customary fastening means, such as nails, to be driven through each of the panels. The inclined surfaces or sides of the bars 89 prevent lifting of the panels 86 and 87 from the plywood panels 85 but do restrict movement thereof trans-

versely of the building structure to accommodate thermal expansion.

In the assembly of the roof sheathing 63, the plywood panels 85 are first positioned on the truss units 47 and secured to the flanges of the roof truss arms 50 by suitable fastening means. As best shown in FIGURE 23, the panels 85 terminate at the web portions of the truss units 47 so that the marginal edges of two adjacent panels will be in contacting engagement when the modules or the building structure are completely assembled. The panels 85 adjacent the end wall 44, however, extend a distance beyond the truss 47d to form the structural base for the overhang. The insulation panels 86 and the roof skins 87 are then placed on the plywood roof panels 85 and the roof batten bar 89 then placed between each of the insulation panels and roof skins and secured to the plywood panels 85. The roof batten structures are then completed by the assembly therewith of a seam cap member 93. The cap member 93 is fabricated from a metal similar to that utilized in the fabrication of the roof skins 87 and consists of an elongated strip having the marginal edges thereof rolled substantially as illustrated in FIGURE 14. Each of the rolled edges forms a channel for receiving the lip member 92 of the roof skins 87. The cap member 93 is readily assembled with the roof structure without the utilization of additional fastening means and is assembled therewith by merely slipping the member longitudinally of the bar 89 with the lip members 92 disposed within the respective channels of the cap member. The roof panels 87 which are locked in position by the cooperative inclined surfaces relative to the bar 89 also lock the cap member 93 to the bar by means of the lip members 92.

The roof insulation panels 86 and their associated roof skins 87 may be of any suitable width, the only limitation on width being that each insulation panel 86 and the overlying roof skin 87 must possess the required structural strength to prevent buckling when subjected to wind forces since the only fastening means is the bar 89 of the roof batten structure 88. In the present embodiment, each of the insulation panels 86 and its associated roof skin 87 is of a width equal to the basic four-foot spacing of the truss units 47. The roof overhang at the end section 43 will, of course, be of a different width, and substantially less than the four-foot standard width of the truss units 47 and thus require panels of less width. During the fabrication of each of the modules 41, 42 or 43, the roof sheathing 63 is also applied. At the end of each of the modules which are to be assembled to an adjacent module, the roof batten structure bars 89 would be attached to only one of the modules. For example, the modules, such as 41 or 42 which are designed to be positioned centrally of the building structure, would have a bar 89 attached to one transverse edge thereof but not to the other. The plywood panel 85 would terminate at the web portion of a truss unit 47 and the bar 89 secured thereto with a portion thereof overhanging the panel. A screw 90 would, therefore, be displaced from the center line of the bar 89 so as to engage the panel 85 a distance inwardly of the marginal edge thereof as illustrated in FIGURE 23. The seam cap 93 would not be assembled therewith until the two adjacent modules are disposed in assembled relationship.

The illustrated embodiment of the building as represented in FIGURE 10 does not utilize a ridge cap or sealing member extending longitudinally of the building structure at the ridge of the roof truss arms. If the ridge cap is deemed necessary such a cap may be constructed similar to the roof batten structures 88 previously described.

The roof overhang or eave structure is formed at the exterior transverse edge of each of the end modules 43. The overhang may be of any desired width or longitudinal extension from the end wall 44. In the present embodiment, it has been found desirable to utilize a width equal to one-half of that of the basic unit spacing of four feet

between the truss units 47, or in this case, approximately two feet. The overhang includes as the structural supporting member an extension of the plywood panels 85 and is thus supported by the truss units 47b and 47d. It is readily apparent that each truss unit 47 will support a roof module width of substantially two feet. Thus the truss units 47b and 47d at the extreme end or exterior end of the end module 43 will be balanced when subjected to substantially equal loads. Decreasing the width of the overhang from two feet would unbalance the truss unit loading and create some twisting effect.

The overhang is constructed in a manner similar to the roof sheathing 63 previously described and applied to the main portions of the modules and includes a roof insulation panel 86a and an associated metal roof skin 87a. An elongated reinforcing member 100, such as a two-by-four, is secured to the marginal transverse edge of the plywood panel 85. The insulation panel 86a is formed with a substantially vertical edge which is disposed in contacting engagement with the reinforcing member 100 while the opposite edge thereof will be inclined for engaging the cooperative, inclined surface of the bar 89. The reinforcing member 100 may be provided with a top facing member or filler member 101 to increase the height thereof to that of the insulation panel 86a to provide a smooth, flat supporting surface for the roof skin 87a. The marginal, transversely extending edge of the roof skin 87a adjacent the roof batten structure 88 is formed with a flanged structure similar to that previously described and including an inclined edge portion 91a and a lip member 92a extending parallel to the main body of the skin and in overlying relationship thereto. The roof batten structure 88 thus located at the truss units 47b and 47d will also serve to retain this edge of the overhang insulation panel 86a and roof skin 87a in contact with the supporting plywood panel 85. A fastening means is also provided for retaining the outer transverse edge of the roof skin 87a in its proper relationship to the reinforcing member 100 and filler member 101 without the utilization of fastening means such as nails driven through from the upper surface of the skin 87a. For this purpose a facing member 102 consisting of a relatively thin board disposed in a vertical plane is secured to the reinforcing member 100 at the outer edge thereof. The overhang roof skin 87a extends a distance outwardly from the facing member 102 with the transverse marginal edge thereof turned downwardly and under the main body portion thereof forming a channel 103. A sheet metal facing plate 104 is then fastened to the facing board 102. The facing plate 104 is formed with a flange member at the upper edge thereof which extends outwardly from the facing member 102 and into a channel 103 of the roof skin. The opposite edge of the facing plate 104 is also formed with a flange which extends under the facing member 102. A fastening means comprising a plurality of nails driven through the lower flange of the facing plate 104 into the facing member 102 may be utilized to retain the plate in position. The plate 104 will thus prevent vertical movement of the roof skin 87a at the outer edge thereof while the inclined flange member 91a will prevent vertical movement at the edge thereof adjacent the roof batten structure 88. Lateral movement or movement longitudinally of the building structure of the overhang roof skin 87a will be prevented by the cap member 93 and the cooperative lip member 92a of the roof skin.

A slip joint structure and weathertight seal is also formed between the exterior sheathing 77 and its siding 77a and the roof sheathing 63. The slip joint is formed by means of an elongated structural member 105, such as a two-by-four, which is fastened to the plywood panel 85 by nails. The member 105 thus extends transversely of the sectional unit or module and depends from the lower surface of the plywood panel 85 with one vertical surface thereof in contacting engagement with a surface of the exterior sheathing 77. The structural member 105, however, is not rigidly secured to the sheathing 77 and the end wall

44 will be free to move relative to the roof. The slip joint is made substantially weathertight by means of a cap plate 106 attached to the sheathing 77 and a facing plate 107 fastened to the structural member 105. The cap plate 106 is formed from an elongated strip of sheet metal having a pair of offset flange members interconnected by a web portion. One of the flange members is disposed in contacting engagement with the exterior sheathing 77 and is rigidly secured thereto by suitable fastening means. The other flange member is disposed a distance outwardly from the sheathing 77 equal to the width of the web portion and extends downwardly forming a channel with the sheathing 77 to receive the upper edge of the siding 77a. The facing plate 107 is also formed from an elongated strip of sheet metal with oppositely directed flanges 108 and 108a. The flange 108 extends under the structural member 105 and includes a lip portion extending downwardly in overlapping relationship to the upper flange of the cap 106. A suitable fastening means is utilized to secure the facing plate 107 to the structural member 105. Since there is no rigid connection formed between the facing plate 107 and the cap plate 106, these members are free to move relative to each other and form a weathertight slip joint.

If desired, the overhang may be completely metal sheathed by the addition of a sheet metal panel 109 which extends transversely of the building and is of a width to cover the lower surface of the plywood panel 85 which extends outwardly from the structural member 105. The upper flange 108a of the facing plate 107 is turned outwardly from the structural member 105 in parallel spaced relationship to the plywood panel 85. The lower flange of the facing plate 104 is preferably of a width to extend a distance under the panel 85 in overlapping relationship. Thus, the panel 109 will be supported on the flanges of the facing plates 104 and 107 in contacting engagement with the panel 85. If necessary, additional support may be provided by means of a plurality of nails 110 driven through the panel 109 into the plywood panel 85.

The longitudinally extending eave portions of the roof arranged along the sides of the building structure are formed in a similar manner. Each of the longitudinal eaves includes a structural member consisting of an extension of the plywood 85. Secured to the upper surface of the plywood panel 85, at the extreme edge thereof, is a reinforcing member 111, such as a two-by-four, and a filler block 112. The combined heights of the reinforcing member 111 and the filler block 112 is substantially equal to that of the insulation panel 86 which extends to the reinforcing member 111. A facing member 113 also extends longitudinally of the module and is fastened to the reinforcing member 111. The metal roof skins 87 extend over the top of the insulation panel 86 and filler block 112 and the facing board 113 with the longitudinal marginal edge thereof turned downwardly and inwardly forming a flange-receiving channel 114. A metal facing plate 115 is fastened to the facing member 113. This facing plate is also formed with oppositely directed flanges with one of the flanges inserted in the channel 114 and the other flange extending under the facing member 113. A siding cap 116 is also provided to form a weathertight seal between the exterior siding 82 and the sheathing 61. The cap member 116 is formed with an offset flange portion extending outwardly and downwardly from the sheathing 61 forming a channel therewith to receive the upper edge of the siding 82. The opposite edge of the cap is also flanged with the flange extending outwardly from the sheathing 61 parallel to the plywood panel 85. In this instance, it is unnecessary to accommodate relative movement between the side sheathing 61 and the roof sheathing 63; therefore, the cap member 116 is rigidly attached to the side sheathing. To completely metal sheath the eave, a metal panel 117 is disposed in contacting engagement with the undersurface of the panel 85 between the sheathing 61 of the wall and

the facing member 113. The panel 117 is supported in position by the flange members of the facing plate 115 and the cap member 116.

Since the truss units 47 are subjected to flexing movement in a vertical plane, it is necessary that all interior walls and partitions be constructed and supported so as to be unaffected by such flexing movement of the truss units 47. As an example of an interior wall or partition arrangement, FIGURE 11 diagrammatically illustrates a typical floor plan. The specific identity of each room is immaterial and the interior walls may be arranged otherwise than as illustrated. In general, the interior walls and partitions will be disposed either transversely of the building or longitudinally thereof. To avoid stressing any of the interior walls, it is necessary that a slip joint construction be provided at the marginal edges of any of the interior walls that abut the floor, the roof or the vertical walls of the building structure. The truss units are designed to be self-supporting and do not need the support that is usually provided by the interior walls in conventional building structures. For this reason, it is unnecessary to so construct the interior walls with more structural strength than required for their own support and miscellaneous household items that may be attached thereto.

A typical slip joint structure at the juncture of a longitudinal wall such as 120 and the end wall 44 is illustrated in FIGURES 17 and 18. The interior longitudinal wall 120 is shown in FIGURE 11 to be located at substantially the center of the building structure. Such a wall, however, may be located at either side of the center of the building or at an angle to the end wall 44. As an interior wall such as 120 is not designed to be a load-supporting wall, the wall may be fabricated from materials of relatively low structural strength. The walls in the illustrated embodiment are fabricated from a pair of relatively thin, parallel spaced skin members 121 and 122 which may be bonded to a central core 123. The central core 123 may be formed from any of the well-known foamed styrenes which possess the requisite structural strength, in combination with the skins 121 and 122, and will provide the desired acoustical insulation characteristics. The skin members 121 and 122 extend a distance from the edge of the core member 123 and form a channel to receive a retaining member 124. The retaining member 124 may either be an elongated strip of wood or a plurality of relatively spaced, short blocks, and are secured to the interior sheathing 75 of the wall 44. The retaining member 124 is vertically disposed and serves to maintain the wall 120 in a vertical position. When assembling a longitudinal wall such as 120 in a building structure, the wall is preferably positioned relative to the interior sheathing 75 of the end wall 44 to space the skin members 121 and 122 a distance from the sheathing 75, as shown. Thus, the interior wall 122 may move relative to the wall 44 either vertically or longitudinally of the building structure. A finished appearance may be readily provided by the inclusion of vertically disposed quarter-rounds 125 adjacent each of the skin members 121 and 122. The quarter-rounds are attached to the sheathing 75 with a flat surface portion thereof in contacting engagement with the exterior surface of the respective skin members 121 and 122. Although the skin members 121 and 122 may move transversely relative to the interior sheathing member 75, the joint therebetween will not be exposed because of the quarter-rounds 125.

Transversely extending interior walls such as 126 and 127 are also connected to the longitudinal side walls of the building structure by similar slip joints. The transverse interior walls 126 and 127 are fabricated similar to the longitudinal walls 120 and include a pair of spaced parallel skin members 128 and 129 which are bonded to a central core 130 also formed from a suitable foamed styrene for acoustical and structural strength with the marginal edges of the skin members 128 and 129 extend-

ing a distance outwardly therefrom. The marginal edges of the skin members 128 and 129 will thus form a channel to receive a retaining member 131. The retaining member 131 is vertically disposed and fastened to an interior flange of the side column 49 of a truss unit 47. The wall 126 is disposed relative to the side column 49 so that the vertical edges of the skin members 128 and 129 will be spaced a distance from the interior flange of the truss unit 47. Thus, the wall 126 will not be affected by relative vertical movement of the side column 49 or by transverse movement thereof. A finished appearance at the joint is provided by a pair of facing plates 132 and 133 which are rigidly secured to the retaining member 131 but spaced therefrom by suitable spacing members 134. Each of the facing plates 132 will thus form a channel with the retaining member 131 to receive the respective skin members 128 and 129 of the interior wall. The spacing of the skin members 128 and 129 relative to the flange of the side column 49 must necessarily be adjusted to accommodate the spacing members 134 without sacrificing the necessary clearance for transverse movement. As shown in FIGURE 20, the wall 126 is positioned longitudinally of the module so that the exterior surface of the skin member 129 is flush with the lip portion of the flange of the truss unit and the facing plate 133 must necessarily extend over the lip portion thereof into contacting engagement with the interior sheathing 62.

Each of the interior walls, either the longitudinal walls such as 120 or the transverse walls such as 126 and 127, must be retained in position on the floor by means of a slip joint. A typical floor and wall slip-joint structure is illustrated in FIGURE 25. A longitudinal wall such as 120 is shown positioned on the floor sheathing 60; however, it is to be understood that the slip-joint structure is applicable to all other interior partition walls. The skin members 121 and 122 thereof extend downwardly from the core 123 forming a channel to receive a retaining member 135 which is rigidly secured to the floor sheathing 60 by a suitable means such as screws. Assuming for the moment that the floor sheathing 60 is unflexed and is essentially horizontal, the edges of the skin members 121 and 122 would be continuously supported on the upper surface thereof. Should the floor be flexed, however, the sheathing 60 may move vertically relative to the wall 120 without affecting the wall itself. During such flexing movement, a gap or space may appear between portions of the abutting edges of the skins 121 and 122 and the floor sheathing 60. For purposes of appearance, a quarter-round molding 136 is fastened to the floor sheathing 60 at each side of the wall with one flat surface thereof vertically disposed in contacting engagement with the exterior surface of the adjacent skin member 121 or 122. Any space appearing between the edge 55 of the skin members 121 and 122 and the floor sheathing 60 will not be visible.

The upper edge of the transverse and longitudinal walls must also be connected to the roof trusses or ceiling by means of slip joints. The slip joint construction for a longitudinal wall such as 120 is illustrated in FIGURES 21 and 22. The longitudinal wall 120a illustrated in FIGURES 21 and 22 is disposed at one side of the center of the building structure but a similar slip joint construction may be utilized, with obvious modifications, for supporting the upper edge of a longitudinal interior wall 120 aligned with the center of the building. The slip joint structure includes a longitudinally extending retaining member 138 which is fastened to the lower flange of the roof truss arms 50 by a suitable fastening means such as screws. The retaining member 138 may be formed from a wood structural member such as a two-by-four having a filler block 139 secured to one vertical edge thereof to obtain a combined thickness substantially equal to the spacing between the skin members 121a and 122a of the interior wall. Since the retaining member 138 and filler

block 139 extend longitudinally of the building, the upper surface thereof must be beveled to correspond to the slope of the roof truss arms 50 in order that the retaining member and filler block will depend vertically. Vertically disposed facing plates 140 and 141 are attached to the retaining member 138 and filler block 139, respectively, and form channels therewith for receiving the skin members of the interior wall 120a. Spacing members 140a and 141a are utilized to maintain the facing plates 140 and 141 in proper spaced relationship to the retaining member 138 and filler block 139. Each of the facing plates 140 and 141 extends a distance downwardly to overlap the adjacent skin member of the interior wall and the spacing between the upper edge of each of the skin members 121a and 122a and the spacing members 140a and 141a will not be visible.

In construction the slip joint, the spacing between the upper edge portions of the core 123a of the wall and the skin members 121a and 122a on the one hand and the lower edge portions of the spacing members 140a and 141a and the retaining member 138 and associated filler block 139 on the other hand must be adequate to accommodate the maximum deflection occurring at the location of the wall. The degree of deflection is greatest at the roof ridge diminishing toward the side columns and the walls may be constructed with spacing in accordance therewith.

The upper marginal edges of the facing plates 140 and 141 of the longitudinal wall 120a shown in FIGURES 21 and 22 terminate at the marginal edge of the flange lip of the roof truss arm 50. Accordingly, there are a series of notches formed in the upper edge of each of the facing plates to receive the flanged portions of each of the truss arms 50. Termination of the face plates 140 and 141 at this particular point is to accommodate an acoustical type ceiling panel 142. A ceiling panel 142 of this type is fabricated from a suitable material possessing the desired acoustical insulating properties and having sufficient structural strength as to be rigid when supported at the marginal edges thereof for a span equal to the distance between each of the truss units 47. Each of the ceiling panels 142 is of a width so as to extend into the interior of the channel of each of the truss units and the panels are supported on the upturned flange lip of each truss unit 47. Thus, the panels 142 may be quickly and easily intalled or removed by merely tilting each of the panels sufficiently so as to be inserted in between pairs of the roof truss arms 50. Since the ceiling panels are seldom, if ever, subjected to any external disturbing forces, it is unnecessary to utilize any rigid type of fastening means to maintain the panels in their respective positions. With the facing plates 140 and 141 constructed as previously described, a smooth joint will be formed between the facing plates and the ceiling panels 142 providing a finished appearance. Flexing of the truss units 47 in a vertical direction as previously described when subjected to varying load conditions will not affect this joint since the facing plates 140 and 141 are secured to the roof truss arms and will move therewith in accordance with the flexing movement as will the ceiling panels 142.

Each of the transversely extending interior walls such as 126 must also be connected to the roof truss arms 50 by means of a slip joint construction, as best shown in FIGURE 24, and similar in construction to that described previously for the longitudinal walls. The joint includes a retaining member 145 which is attached to the flange of a roof truss arm 50 by a suitable fastening means such as wood screws. The retaining member 145 depends downwardly a distance from the roof truss arm 50 to extend between the spaced skin members 128 and 129 of the wall 126. A filler block 145a is also fastened to a vertical surface of the retaining member to obtain a combined thickness substantially equal to the internal spacing of the skin members 128 and 129. A pair of facing

plates 146 and 147 are attached to the retaining member 145 in spaced relationship thereto by means of screws extending through spacer members 146a and 147a, respectively. A more finished appearance is provided in this instance by extending the face plate 147 upwardly to cover the flange lip of the truss unit 47 and terminating in contacting engagement with the ceiling panel 142.

The vertical spacing between the upper marginal edges of each of the skin members 128 and 129 and the respective spacing members 146a and 147a as well as the spacing between the opposed edge surfaces of the core 130 of the wall and the lower surface of the retaining member 145 is determined by the amount of relative vertical flexing movement which may occur between the floor and the roof truss arms 50. As previously indicated, the vertical flexing movement of the roof truss arms 50 and the floor joists 48 is not uniform over their entire length in respect to a fixed vertical reference point. The portions of the roof truss arms 50 adjacent the center or the roof ridge of the building will experience a relatively greater vertical movement than the portions of the truss arms connected to the side columns 49. The spacing of the relatively movable slip joint members extending transversely of the building structure must accordingly accommodate the variations in vertical flexing movement. In the illustrated embodiment, the retaining member 145 is formed to have a greater width adjacent the portions of the roof truss arms 50 at the side columns 49 than at the roof ridge as shown in FIGURE 26. The facing plates 146 and 147 must remain at a substantially uniform width for purposes of appearance.

In respect to the construction of a transverse wall to accommodate variations in vertical flexing movement, it must be remembered that the ends walls 44 must also be formed in a similar manner. The spacing between the upper ends of the studs 70 in the end wall and the lower flange of the roof truss arm 50 must, therefore, be sufficient to accommodate the vertical flexing movement at the location of a particular stud. Similarly, the interior sheathing 75 must be spaced below the bolts 64 extending through the truss units 47b and 47d a distance to accommodate the maximum deflection that may occur at each bolt location. The slip joint structure of the exterior sheathing 77 and its associated siding 77a relative to the structural member 105 and the roof panel 85 is also constructed to have adequate clearance for accommodation of the maximum deflection. The spacing is a maximum at the roof ridge diminishing to a minimum at the side columns 49 in a manner similar to that illustrated in FIGURE 26.

The transversely extending interior wall sections 126 and 127 previously described herein have been designed to be installed in planes aligned with the truss units 47. A particular floor plan or room arrangement, for more economic space utilization, may require that a transversely extending interior wall be positioned intermediate a pair of truss units 47. An example of such a wall installation may be a closet partition 150 as indicated in FIGURE 11. The closet partition 150 would be connected to the floor by means of a typical slip joint structure illustrated in FIGURE 25 and would be rigidly connected to a longitudinally extending interior wall by conventional rigid construction methods. The upper edge of the interior wall 150, however, must be provided with a suitable slip joint structure to permit its vertical movement relative to the truss units 47 and roof sheathing 63. Referring to FIGURE 27, illustrating in detail the slip joint construction of the interior wall 150, the wall is constructed as previously and includes a pair of parallel spaced skin members 151 and 152 bonded to a central core member 153. The skin members 151 and 152 extend a distance upwardly into the space between a pair of adjacent roof truss arms 50 and form a channel with the upper surface of the core 153. A rigid structural member 154 is disposed between the

upper marginal edges of the skin members 151 and 152 and is rigidly secured thereto by suitable fastening means, nails for example. The member 154 preferably extends substantially the length of the upper marginal edge of the partition 150. Rigidly attached to the upper surface of the structural member 154 are one or more spacing bars 155. Each spacing bar 155 extends transversely relative to the partition 150 and is of a length to position the ends thereof in contacting engagement with the vertical web portions of the respective roof truss arms 50. The spacing bars 155, however, are not rigidly secured to the roof truss arms 50 to permit relative vertical movement as the truss units 47 flex in a vertical plane. The number of spacing bars 155 that may be utilized is determined by the length of the wall 150. For a relatively short closet partition, it is only necessary to provide one bar at the free end of the partition. For other interior walls of the closet partition type 150, it may be necessary to provide a plurality of the bars at uniformly spaced intervals.

A pair of acoustical type ceiling panels 156 are required to form the interior ceiling structure with a partition such as 150. An elongated angle member 157 is secured to the upper marginal edge of the respective skin members of the wall to support one edge of the respective ceiling panel 156. The angle members 157 are positioned vertically so that a flange thereof extends laterally from the skin member will be at the normal elevation of the edge of the lip portion of the roof truss arm and is, therefore, sloped accordingly. Thus, the ceiling panels 156 will be supported in a plane parallel to and aligned with the adjacent ceiling panels 142.

The beams 45 and 46 which extend longitudinally of the building structure to support the several truss units 47 are fabricated from conventional structural steel shapes such as an I-beam although it is to be understood that other beam constructions may be utilized. For example, prestressed concrete beams may be utilized for a particular installation. The length of the beams 45 and 46 must be at least equal to the length of the building structure to provide a support for all of the truss units 47. If desired, the beams 45 and 46 may extend a distance outwardly from one or both ends of the building structure to permit the addition of other modules in accordance with future expansion plans without the necessity of altering the foundation structure. In the interim before completion of such expansion, the beam extensions may be utilized to support a porch or sun deck.

Each beam 45 and 46 is supported on foundation piers 160 as best shown in FIGURES 28, 29 and 30. Each of the foundation piers 160 is of the conventional reinforced concrete type having a footer 161 disposed a distance below the normal ground level to provide adequate support for the building structure which will be carried thereon. A bearing plate 162 is preferably welded to the lower flange of the beam to provide an enlarged pier-contacting surface for better distribution of the compression forces. The bearing plate 162 is secured to the foundation pier 160 by means of a pair of foundation bolts 163 embedded therein. The number of foundation piers 160 that may be required for a particular installation is dependent on the soil structure at the specific building site and the weight of the building structure to be supported thereon. The length of the building structure is also a factor to be considered in determining the number of piers required to avoid the necessity of utilizing a relatively large size beam. In the illustrated embodiment, two foundation piers 160 are provided for each of the longitudinal beams 45 and 46 with the piers being positioned a distance inwardly from each end of the beam to further reduce the length of the unsupported spans. Increasing the number of foundation piers 160 will reduce the unsupported span length of a particular beam and, therefore, reduce the size of the required beam.

The truss units 47 extend transversely relative to the

beams 45 and 46 and are supported on the upper flange of the beams. As shown in FIGURES 29 and 30, the joist beam portions 48 of the truss units are supported on the beams 45 and 46 and are rigidly secured thereto by a fastening means to prevent shifting of the building structure. Preferably, a suitable thermal and acoustical insulating barrier pad 165 is disposed between the upper surface of the beams 46 and 45 and the lower flanges of the truss units. The barrier 165 consists of a flat strip of material possessing the desired structural strength to support the truss units. The barrier will thus prevent the transfer of heat between the beams 45 and 46 and the truss units 47 supported thereon as well as any vibrations transmitted through the ground to the foundation piers 160. The fastening means utilized in clamping the truss units to the beams is also constructed to provide a thermal and acoustical barrier and readily permit detachment of the truss units. The particular fastening means illustrated in FIGURES 29 and 30 comprises an

L-shaped bracket 166 having a length substantially equal to the combined width of the flanges of two of the truss units 47. The bracket 166 is disposed with the shorter leg thereof in contacting engagement with the flanges of the truss units 47 and the longer leg extending substantially parallel thereto and underlying the flange portion of the beams 45 or 46 to which it is clamped. A barrier strip 167 of a thermal and acoustical insulating material is also disposed between the longer leg of the bracket and the undersurface of the flange of the beam. A pair of

bolts 168 extend through the longer leg of the bracket 166 and are threaded into nuts 169 welded on the flanges of the respective truss units 47. Tightening of the bolts 168 will cause the bracket 166 to pivot about a fulcrum consisting of the point of contact of the shorter leg and the truss units 47 to draw the end of the longer leg thereof toward the flange of the beam and compress the barrier strip 167.

An electrical ground may be conveniently provided by interconnecting the reinforcing members of the foundation piers 160 with a ground rod 170 driven into the ground and the foundation bolts 163 which are mechanically coupled to the beams 45 and 46. A suitable electrical bond such as indicated at 171 (FIGURE 29) may also be formed between each of the truss units 47 and the beam on which it is supported. A safe ground is thus provided for all electrical apparatus that may be contained within the building. In addition, the application of lightning protection such as the usual conventional rods, may be conveniently installed by merely connecting such rods with the truss units 47.

A modification of the roof batten structure is illustrated in FIGURE 31. The modified structure eliminates the necessity of the elongated bar 89 which further simplifies manufacturing and assembly of the building structure. Only the roof sheathing is illustrated in FIGURE 31 with the supporting roof truss arms of each of the truss units normally associated therewith eliminated from this view. The roof sheathing is of the same general form as previously described and includes a three-quarter inch plywood roof panel 175 which is adapted to be secured to the truss units. Disposed on the upper surface of the plywood roof panel 175 are the insulation panels 176. Placed on the upper surface of the insulation panels 176 are the roof skins or panels 177 which are fabricated from a sheet metal such as aluminum. The marginal edges of each of the roof skins 177 which extend transversely of the building or module are turned upwardly and over the main body portion of the panel to form substantially closed channels. Each of the channels is of a generally rectangular cross section formed with an opening between the downturned edge portion and the main body portion of the panel. A cap member 180 of elongated channel form is adapted to be slipped over the channel portions 178 of adjacent roof skin 177 and form a substantially weathertight seal therewith.

Each of the flange portions of the cap member 180 are turned inwardly and upwardly to form an upwardly-opening channel 181 which becomes interlocked with the channels 178 of the roof skins when assembled therewith to form a weathertight seal. To maintain the cap member 180 in its position on the roof, a plurality of screws 182, extending downwardly through an opening in the web portion of the cap member 180, engage the plywood roof panels 175. The screws 182, in cooperation with the cap member 180, provide a downwardly directed force to retain the roof skins 177 and insulation panels 176 in cooperative engagement with the roof panels 175. Longitudinal expansion of the cap member 180 will not be restricted substantially by the screws 182 since the length thereof will be sufficient to permit bending in a plane longitudinally of the cap member 180. Also, the roof skins 177 may expand or contract in accordance with temperature changes without distortion as the interlocking channels 181 and 178 permit relative movement.

A second modification of the roof batten structure is illustrated in FIGURES 32, 33 and 34. In this modification the roof sheathing also consists of a plywood roof panel 185, an insulation panel 186 supported on the upper surface thereof, and a sheet metal roof skin placed on the surface of the insulation panel 187. The marginal edges of each of the roof skins at transversely extending joints are turned upwardly to form inclined flanges 188 with the marginal edge portion substantially vertically disposed. Referring to FIGURES 33 and 34 illustrating a transverse joint, a plurality of generally L-shaped fastening straps 189 are spaced along the joint with one leg thereof in contacting engagement with the roof panel 185 and the opposite leg extending vertically upwardly therefrom between the flanges 188 of the adjacent roof skins 187. The lower horizontal leg of the fastening strap 189 is rigidly secured to the roof panel 185 by suitable fastening means such as nails and the roof panels 187 are secured to the upwardly extending leg of the fastening strap 189 by a single rivet extending through the flanges 188. The metal roof skins 187 will, therefore, be relatively free to move transversely of the building under thermal distortion forces. Since the rivet 190 forms a pivot point for the fastening strap 189, the strap being fabricated from a relatively thin sheet metal which will not be resistant to racking forces and may readily bend transversely of the building structure without serious deformation. The inclined flanges 188 of the roof skins 187 also permit thermal expansion and contraction thereof longitudinally of the building structure. However, the straps 189 are effective in retaining the roof skins 187 on the roof panels 185.

Sealing of the joint formed by the flanges 188 of two adjacent roof skins 187 is accomplished by a thermoplastic sealing cap 191. The sealing cap 191 is molded in a U-shaped channel form for receiving the upwardly-extending flanges 188. Further sealing of the joint is accomplished by the addition of an inverted U-shaped metal channel 192 referred to herein as a seam cap. The seam cap 192 extends longitudinally of the seam with the flanges disposed on opposite sides of the flanges 188 of two adjacent roof skins 187. A sheet metal screw 193 is driven through the web portion of the seam cap 192 at the location of each of the fastening straps 189 and engages a portion of the strap 189 to maintain the seam cap 192 in position. For this purpose, the upper marginal end of the fastening strap 189 is formed to provide a substantially horizontal portion 194 into which the screw 193 is threaded. An asphaltic sealing compound may be placed under the head of each of the screws 193 to form a seal with the seam cap 192.

A ridge cap of this modified form is illustrated in FIGURE 32. As is readily apparent from the drawings, the ridge cap structure also includes a plurality of fastening straps 195 secured to the roof panel 185 along the roof ridge. The roof skins 187 are also formed with

upwardly extending, inclined flanges 196 at the ends extending parallel to the ridge. The flanges 196 are similarly secured to the vertical portion of the fastening straps 195 by means of a rivet 197. The upper marginal end 5 of the fastening straps 195 are also formed to provide a substantially horizontal portion for receiving a sheet metal screw 198 extending through the web of a seam cap 199. A thermoplastic sealing cap 200 similar to that previously described for a transverse joint is applied to the upper marginal edges of the roof skin lip members 197 to complete the weathertight seal.

At the joint between adjacent modules, the seam constructions would be modified to permit assembly of the units. In respect to the transversely extending joints as 15 illustrated in FIGURE 33, only the roof skin panel 187 overlying the roof sheathing member 185 in which the fastening strap 189 is attached would be secured by a rivet to the upper leg of the fastening means. Alternately disposed fastening straps 189 would be reversed from the position illustrated in FIGURE 33 and secured to the roof panel 185 of the opposite module. The roof skins 187 adjacent the transverse edges of each adjoining module would thus be rigidly secured to the roof panels 185. The seam cap 192 and sealing cap 191 would not be assembled 20 with the module at this time. When the two modules are assembled at the building site, the flange 188 of the roof panel 187 of the opposite or adjacent module would be disposed in contacting engagement with the upper vertical leg of the fastening strap 188. A thermoplastic sealing cap 191 would then be applied to the flanges 188 and the seam cap 192 assembled therewith.

An alternate form of fastening means for connecting two adjacent truss units 47 together is illustrated in FIGURES 35 and 36. The alternate form of connector consists of a T-member 201 extending through the web portions of two adjacent truss units 47 and secured thereto by means of a locking wedge 202. The T-member 201 comprises a short section of a T-rail having a leg portion inserted through aligned rectangular slots formed in the 30 truss units 47. The head of the T-member 201 will thus be in contacting engagement with the surface of the web of one truss unit 47. The locking wedge 202 is disposed in a slot formed in a leg of the T-member 201 with a vertical edge portion adjacent the web portion of the truss unit 47. To assemble a building structure utilizing this 35 form of connector, it is only necessary that the adjacent modules be placed in contacting engagement to permit insertion of the leg portion of the T-member 201 through the aligned slots in the truss units 47. The wedge member 202 is then merely dropped through the slot in the leg portion of the T-member 201. Disassembly of the 40 building structure may, therefore, be readily accomplished by merely removing the wedge and separating the separate 45 modules.

A further modification of the assembly of the sheathing members to the truss units is illustrated in FIGURES 55 37 and 38. In this modification, nailing strips 205 are applied to the exterior flanges of the truss units 47 to which sheathing members, such as the walls, roof and floor, may be attached. Utilization of the nailing strips 60 205 greatly facilitates the fabrication of the building as a considerable amount of time is saved when the nailing strips are applied to the respective truss units 47 at the time of assembly of the truss units. Thus, when each module is assembled, the several sheathing members, such 65 as those for the wall, roof and floor, may be readily applied with the usual carpenter's tools, such as a hammer or automatic nailing gun. It is unnecessary to consume time at this point in the assembly process in applying the sheet metal screws or hardened steel screw nails 70 that are required for attaching materials to the metal truss units 47. FIGURE 37 illustrates an end wall structure similar to that of FIGURE 14 wherein nailing strips 205 are applied to the upper surfaces of the flanges of the two adjacent truss units. The plywood roof panel 206 may, 75 therefore, be applied directly to the nailing strips 205.

Also the construction of the overhang is modified slightly from that illustrated in FIGURE 14; however, the structure still incorporates a slip joint between the roof sheathing and the end wall 44a which is similar to that previously described and illustrated in FIGURE 14.

Similarly, FIGURE 38 illustrates a modification of the side wall structure. In this modification the nailing strips 205 are applied to both the internal and external flanges of the side columns 49 of the truss units 47. An interior sheathing 210 may thus be readily applied to the nailing strips 205. A slip joint construction of an interior, transversely extending wall is also illustrated in this figure. The construction of the slip joint is substantially identical with that previously described except that vertically extending quarter-rounds 211 are utilized to conceal the juncture of the skin members of the transversely extending wall relative to the interior sheathing 210. An exterior sheathing 212 is similarly applied to the nailing strips 205 attached to the exterior flanges of the truss units 47. A siding 213 may then be applied to the exterior sheathing 212.

The roof of the building structure is fully insulated by means of the insulation panels supported on the upper surface of the plywood roof panels and it is therefore unnecessary to provide additional insulation other than for acoustical purposes in the interior of the buildings. In building structures not generally utilized for residential purposes such as those that are utilized only as vacation homes, it may be desirable to eliminate the acoustical ceiling panels. To improve the appearance of the interior surface of the roof for a building structure of this type, referring to FIGURE 39, the roof truss arms 50a may be reversed in their relative positions to form a box beam. The open portions of the C-shaped channels forming the roof truss arm 50a would thus face each other while the web portions would form the vertical sides of the box beam. An elongated bolt 215 is utilized to secure the truss arms 50a together. A roof sheathing 216 is supported on and attached to the upper flanges of the truss arms 50a with the lower flanges forming a closed bottom for the beam. In the formation of a truss unit of this type, only the roof truss arms 50 would be reversed in their position. The side columns 49 and the floor joists 48 would remain as previously described in order that the web portions thereof would be in contacting engagement when the truss units are placed together.

The modules are constructed at the factory with either an 8 or 12 foot longitudinal dimension to facilitate transportation to a building site. For transportation, the modules would present a load width of either 8 or 12 feet and permit movement from the factory to a building site by means of a tractor-drawn trailer or rail car. A module such as 41 or 42 without any interior partitions or walls is shown in FIGURE 40 supported on a tractor trailer A. The modules are constructed to be self-supporting and may be readily lifted for placement on such a trailer at the factory and removal at the building site and positioning on a foundation structure including a pair of longitudinal beams 45 and 46.

Another form of transportation of each building section or module may be achieved by merely bolting an axle or axles with the associated wheels, tires and brakes, to the floor joists 48 thereof at the same time, providing a detachable hitch which is in turn bolted to the building section at one end or the other. The integral steel truss units 47 of the building are strong enough to take the place of the standard transport trailer frame, thus achieving a lower cost of transportation by virtue of the elimination of the requirement for investment in a more conventional highway trailer transport rig.

It will be apparent from the above that my invention provides for a building structure which is composed of standardized or segmentized transverse sections or modules which in the final assembly are clamped together in cooperative weathertight relationship. Any number of these sections may be used in the building and

sections can be readily added or removed. The sections are so supported by the longitudinally extending beams that little site preparation is required. Each section is structurally complete in itself so that handling without racking is possible in delivering and installing each section. Also, the structure of each section is such that when it is assembled in the building, it will adequately withstand forces developed by various weather and other conditions even though they may be unusual. Composite trusses form the basic structural units of each of the modules and are designed for limited flexing movement to minimize the size and weight of the trusses and the overall weight of the building structure. All joints between relatively movable members are constructed to permit such relative movement resulting from flexing of the truss units without damage to the members. The basic transverse truss unit of each building section can be manufactured readily at a shop or factory and a module can be made from a plurality of these units at the same location. Each module may be complete as to interior and exterior finish so little work at the site is necessary. Thus, maximum efficiency and minimum cost can be obtained. Ease of assembly at the site, modification by removal or addition of modules, or complete removal and relocation of the entire structure result from my invention.

Although I have brought out many advantages of my structure, other advantages will be readily apparent.

Having thus described this invention, what is claimed is:

1. In a building structure, a transverse building section comprising a plurality of framework truss units disposed in longitudinally spaced relationship and structurally joined together by structural members extending longitudinally therebetween, each of said framework truss units extending transversely of the building structure and disposed in an upright vertical transverse plane with the planes of the respective truss units being parallel with each other, main supports extending longitudinally relative to said truss units on which said truss units rest and which are disposed in transversely spaced relationship, each of said truss units being a continuous closed framework composed of a plurality of continuous frame beam members capable of taking both tension and compression and having adjacent ends angularly disposed with reference to each other and connected together by rigid moment-transmitting joints which maintain the angular disposition free of bracing struts extending angularly relative to the frame beam members so that the framework is formed solely by said beam members which extend in the common transverse plane and will transmit bending moments from one to the other; said beam members consisting of: a lower floor joist beam resting on said main longitudinal supports and having ends projecting outwardly in opposed directions beyond said supports, a pair of upright side column beams connected respectively to the outer ends of said floor joist beams by said rigid joints, and a pair of inwardly and upwardly angularly extending, cantilever-type roof truss arm beams connected to upper ends of the side column beams by said rigid joints and having their inner ends converging and connected together by one of said rigid joints to provide a peaked roof truss; said continuous framework of each truss unit resting on said main longitudinal supports and consisting of said rigidly connected frame beam members having said rigid joints but providing a composite framework which is capable of supporting predetermined design loads within allowable limits of vertical flexure about said main supports which serve as fulcrums but capable of flexing vertically about said supports upon static loading of any of said beam members in the plane of the framework which creates bending moments in the framework that are opposed by other bending moments created in the framework and acting in the plane of the framework; said longitudinally extending structural members joining said framework truss units comprising bracing

members extending longitudinally between and rigidly connected to the respective adjacent longitudinally spaced framework truss units, and serving to structurally join the spaced framework truss units of the building section to prevent racking or distortion of the building section in a longitudinal direction at an angle to the transverse planes of said framework truss units.

2. In a building structure, a transverse building section comprising a plurality of framework truss units disposed in longitudinally spaced relationship and structurally joined together by structural members extending longitudinally therebetween, each of said framework truss units extending transversely of the building structure and disposed in an upright vertical transverse plane with the planes of the respective truss units being parallel with each other, main supports extending longitudinally relative to said truss units on which said truss units rest and which are disposed in transversely spaced relationship, each of said truss units being a continuous closed framework composed of a plurality of continuous frame beam members capable of taking both tension and compression and having adjacent ends angularly disposed with reference to each other and connected together by rigid moment-transmitting joints which maintain the angular disposition free of bracing struts extending angularly relative to the frame beam members so that the framework is formed solely by said beam members which extend in the common transverse plane and will transmit bending moments from one to the other; said beam members consisting of: a lower floor joist beam resting on said main longitudinal supports and having ends projecting outwardly in opposed directions beyond said supports, a pair of upright side column beams connected respectively to the outer ends of said floor joist beam by said rigid joints, and a pair of inwardly extending, cantilever-type roof truss arm beams connected to upper ends of the side column beams by said rigid joints and having their inner ends adjacent and connected together by one of said rigid joints; said continuous framework of each truss unit resting on said main longitudinal supports and consisting of said rigidly connected frame beam members having said rigid joints but providing a composite framework which is capable of supporting predetermined design loads within allowable limits of vertical flexure about said main supports which serve as fulcrums but capable of flexing vertically about said supports upon static loading of any of said beam members in the plane of the framework which creates bending moments in the framework that are opposed by other bending moments created in the framework and acting in the plane of the framework; said longitudinally extending structural members joining said framework truss units comprising a floor web extending longitudinally between and rigidly connected to the respective floor joist beams of adjacent longitudinally spaced framework truss units, and a roof web extending longitudinally between and rigidly connected to the respective roof truss arm beams of adjacent longitudinally spaced framework truss units, said webs serving to structurally join the respective corresponding beam members of the spaced framework truss units of the building section to prevent racking or distortion of the building section in a longitudinal direction at an angle to the transverse planes of said framework truss units.

3. In a building structure, a transverse building section comprising a plurality of framework truss units disposed in longitudinally spaced relationship and structurally joined together by structural members extending longitudinally therebetween, each of said framework truss units extending transversely of the building structure and disposed in an upright vertical transverse plane with the planes of the respective truss units being parallel with each other, main supports extending longitudinally relative to said truss units on which said truss units rest and which are disposed in transversely spaced relation-

ship, each of said truss units being a continuous closed framework composed of a plurality of continuous frame beam members capable of taking both tension and compression and having adjacent ends angularly disposed with reference to each other and connected together by rigid joints free of bracing struts extending angularly relative to the frame beam members so that the framework is formed solely by said beam members which extend in the common transverse plane and will transmit bending moments from one to the other; said beam members consisting of: a lower floor joist beam resting on said main longitudinal supports and having ends projecting outwardly in opposed directions beyond said supports, a pair of upright side column beams connected respectively to the outer ends of said floor joist beam by said rigid joints, and a pair of inwardly extending, cantilever-type roof truss arm beams connected to upper ends of the side column beams by said rigid joints and having their inner ends adjacent and connected together by one of said rigid joints; said continuous framework of each truss unit resting on said main longitudinal supports and consisting of said rigidly connected frame beam members having said rigid joints but providing a composite framework which is capable of supporting predetermined design loads within allowable limits of vertical flexure about said main supports which serve as fulcrums but capable of flexing vertically about said supports upon static loading of any of said beam members in the plane of the framework which creates bending moments created in the framework and acting in the plane of the framework; said longitudinally extending structural members joining said framework truss units comprising bracing members extending longitudinally between and rigidly connected to the respective adjacent longitudinally spaced framework truss units, and serving to structurally join the spaced framework truss units of the building section to prevent racking or distortion of the building section in a longitudinal direction at an angle to the transverse planes of said framework truss units; at least one vertically disposed wall structure incorporated in said building section, and means for yieldably connecting said vertically disposed wall structure to at least one of said framework truss units of said section whereby vertical flexure of the truss unit will not damage said vertically disposed wall structure.

4. In a building structure, a transverse building section comprising a plurality of framework truss units disposed in longitudinally spaced relationship and structurally joined together by structural members extending longitudinally therebetween, each of said framework truss units extending transversely of the building structure and disposed in an upright vertical transverse plane with the planes of the respective truss units being parallel with each other, main supports extending longitudinally relative to said truss units on which said truss units rest and which are disposed in transversely spaced relationship, each of said truss units being a continuous closed framework composed of a plurality of continuous frame beam members capable of taking both tension and compression and having adjacent ends angularly disposed with reference to each other and connected together by rigid joints free of bracing struts extending angularly relative to the frame beam members so that the framework is formed solely by said beam members which extend in the common transverse plane and will transmit bending moments from one to the other; said beam members consisting of: a lower floor joist beam resting on said main longitudinal supports and having ends projecting outwardly in opposed directions beyond said supports, a pair of upright side column beams connected respectively to the outer ends of said floor joist beam by said rigid joints, and a pair of inwardly extending, cantilever-type roof truss arm beams connected to upper ends of the side column beams by said rigid joints and having their inner ends adjacent and connected together by one

of said rigid joints; said continuous truss unit framework resting on said main longitudinal supports and consisting of said rigidly connected frame beam members having said rigid joints but providing a composite framework which is capable of supporting predetermined design loads within allowable limits of vertical flexure about said main supports which serve as fulcrums but capable of flexing vertically about said supports upon static loading of any of said beam members in the plane of the framework which creates bending moments in the framework that are opposed by other bending moments created in the framework and acting in the plane of the framework; said longitudinally extending structural members joining said framework truss units comprising a floor web extending longitudinally between and rigidly connected to the respective floor joist beams of adjacent longitudinally spaced framework truss units, a roof web extending longitudinally between and rigidly connected to the respective roof truss arm beams of adjacent longitudinally spaced framework truss units, and a side wall web extending longitudinally at each side of the building section between the respective upright column beams of the adjacent longitudinally spaced framework truss units and being rigidly connected to said column beams, all of said webs serving to structurally join the respective corresponding beam members of the spaced framework truss units of the building section to prevent racking or distortion of the building section in a longitudinal direction at an angle to the transverse planes of said framework truss units; and a transverse end wall structure for said building section disposed in a transverse vertical plane adjacent a cooperating framework truss unit and having marginal portions in cooperative relationship with the respective beam frame members of said framework truss unit, means for rigidly connecting said end wall structure to the floor joist beam of said truss unit at points corresponding to said main longitudinal supports and means for yieldingly connecting said end wall structure at the remainder of its marginal portions to corresponding portions of said adjacent framework truss unit so as to prevent vertical flexing of said adjacent truss unit relative to said end wall structure without damage thereto.

5. In a building structure, a transverse building section comprising a plurality of framework truss units disposed in longitudinally spaced relationship and structurally joined together by structural members extending longitudinally therebetween, each of said framework truss units extending transversely of the building structure and disposed in an upright vertical transverse plane with the planes of the respective truss units being parallel with each other, main supports extending longitudinally relative to said truss units on which said truss units rest and which are disposed in transversely spaced relationship, each of said truss units being a continuous closed framework composed of a plurality of continuous frame beam members capable of taking both tension and compression and having adjacent ends angularly disposed with reference to each other and connected together by rigid joints free of bracing struts extending angularly relative to the frame beam members so that the framework is formed solely by said beam members which extend in the common transverse plane and will transmit bending moments from one to the other; said beam members consisting of: a lower floor joist beam resting on said main longitudinal supports and having ends projecting outwardly in opposed directions beyond said supports, a pair of upright side column beams connected respectively to the outer ends of said floor joist beam by said rigid joints, and a pair of inwardly extending, cantilever-type roof truss arm beams connected to upper ends of the side column beams by said rigid joints and having their inner ends adjacent and connected together by one of said rigid joints; said continuous truss unit framework resting on said main longitudinal supports and consisting of said rigidly connected

frame beam members having said rigid joints but providing a composite framework which is capable of supporting predetermined design loads within allowable limits of vertical flexure about said main supports which serve as fulcrums but capable of flexing vertically about said supports upon static loading of any of said beam members in the plane of the framework which creates bending moments in the framework that are opposed by other bending moments created in the framework and acting in the plane of the framework; said longitudinally extending structural members joining said framework truss units comprising a floor web extending longitudinally between and rigidly connected to the respective floor joist beams of adjacent longitudinally spaced framework truss units, a roof web extending longitudinally between and rigidly connected to the respective roof truss arm beams of adjacent longitudinally spaced framework truss units, and a side wall web extending longitudinally at each side of the building section between the respective upright column beams of the adjacent longitudinally spaced framework truss units and being rigidly connected to said column beams, all of said webs serving to structurally join the respective corresponding beam members of the spaced framework truss units of the building section to prevent racking or distortion of the building section in a longitudinal direction at an angle to the transverse planes of said framework truss units; and a transverse end wall structure for said building section disposed in a transverse vertical plane adjacent a cooperating framework truss unit and having marginal portions in cooperative relationship with the respective beam frame members of said framework truss unit, means for rigidly connecting said end wall structure to the floor joist beam of said truss unit at points corresponding to said main longitudinal supports and means for yieldingly connecting said end wall structure at the remainder of its marginal portions to corresponding portions of said adjacent framework truss unit so as to permit vertical flexing of said adjacent truss unit relative to said end wall structure without damage thereto; an interior vertically disposed wall in said building section extending longitudinally thereof and abutting said end wall structure, and a yieldable joint between said interior wall and said end wall structure for permitting relative vertical movement therebetween produced by vertical flexing of the truss units in said building section.

6. In a building structure, a transverse building section comprising a plurality of framework truss units disposed in longitudinally spaced relationship and structurally joined together by structural members extending longitudinally therebetween, each of said framework truss units extending transversely of the building structure and disposed in an upright vertical transverse plane with the planes of the respective truss units being parallel with each other, main supports extending longitudinally relative to said truss units on which said truss units rest and which are disposed in transversely spaced relationship, each of said truss units being a continuous closed framework composed of a plurality of continuous frame beam members capable of taking both tension and compression and having adjacent ends angularly disposed with reference to each other and connected together by rigid joints free of bracing struts extending angularly relative to the frame beam members so that the framework is formed solely by said beam members which extend in the common transverse plane and will transmit bending moments from one to the other; said beam members consisting of: a lower floor joist beam resting on said main longitudinal supports and having ends projecting outwardly in opposed directions beyond said supports, a pair of upright side column beams connected respectively to the outer ends of said floor joist beam by said rigid joints, and a pair of inwardly extending, cantilever-type roof truss arm beams connected to upper ends of the side column beams by said rigid joints and having their inner ends adjacent and connected together by one of said rigid joints; said continuous truss unit framework resting on said main longitudinal supports and consisting of said rigidly connected

and connected together by one of said rigid joints; said continuous framework of each truss unit resting on said main longitudinal supports and consisting of said rigidly connected frame beam members having said rigid joints but providing a composite framework which is capable of supporting predetermined design loads within allowable limits of vertical flexure about said main supports which serve as fulcrums but capable of flexing vertically about said supports upon static loading of any of said beam members in the plane of the framework which creates bending moments in the framework that are opposed by other bending moments created in the framework and acting in the plane of the framework; said longitudinally extending structural members joining said framework truss units comprising a floor web extending longitudinally between and rigidly connected to the respective floor joist beams of adjacent longitudinally spaced framework truss units, a roof web extending longitudinally between and rigidly connected to the respective roof truss arm beams of adjacent longitudinally spaced framework truss units, and a side wall web extending longitudinally at each side of the building section between the respective upright column beams of the adjacent longitudinally spaced framework truss units and being rigidly connected to said column beams, all of said webs serving to structurally join the respective corresponding beam members of the spaced framework truss units of the building section to prevent racking or distortion of the building section in a longitudinal direction at an angle to the transverse planes of said framework truss units; a vertically disposed interior wall in said section having a lower edge extending along said floor web, and a yieldable joint between said floor web and said lower edge of said interior wall to permit vertical flexing of said floor web in accordance with vertical flexing of said framework truss units to which it is connected.

7. In a building structure, a transverse building section comprising a plurality of framework truss units disposed in longitudinally spaced relationship and structurally joined together by structural members extending longitudinally therebetween, each of said framework truss units extending transversely of the building structure and disposed in an upright vertical transverse plane with the planes of the respective truss units being parallel with each other, main supports extending longitudinally relative to said truss units on which said truss units rest and which are disposed in transversely spaced relationship, each of said truss units being a continuous closed framework composed of a plurality of continuous frame beam members capable of taking both tension and compression and having adjacent ends angularly disposed with reference to each other and connected together by rigid joints free of bracing struts extending angularly relative to the frame beam members so that the framework is formed solely by said beam members which extend in the common transverse plane and will transmit bending moments from one to the other; said beam members consisting of: a lower floor joist beam resting on said main longitudinal supports and having ends projecting outwardly in opposed directions beyond said supports, a pair of upright side column beams connected respectively to the outer ends of said floor joist beam by said rigid joints, and a pair of inwardly extending, cantilever-type roof truss arm beams connected to upper ends of the side column beams by said rigid joints and

having their inner ends adjacent and connected together by one of said rigid joints; said continuous framework of each truss unit resting on said main longitudinal supports and consisting of said rigidly connected frame beam members having said rigid joints but providing a composite framework which is capable of supporting predetermined design loads within allowable limits of vertical flexure about main supports which serve as fulcrums but capable of flexing vertically about said supports upon static loading of any of said beam members in the plane of the framework which creates bending moments in the framework that are opposed by other bending moments created in the framework and acting in the plane of the framework; said longitudinally extending structural members joining said framework truss units comprising a floor web extending longitudinally between and rigidly connected to the respective floor joist beams of adjacent longitudinally spaced framework truss units, a roof web extending longitudinally between and rigidly connected to the respective roof truss arm beams of adjacent longitudinally spaced framework truss units, and a side wall web extending longitudinally at each side of the building section between the respective upright column beams of the adjacent longitudinally spaced framework truss units and being rigidly connected to said column beams, all of said webs serving to structurally join the respective corresponding beam members of the spaced framework truss units of the building section to prevent racking or distortion of the building section in a longitudinal direction at an angle to the transverse planes of said framework truss units; a vertically disposed interior wall in said section having a lower edge extending along said floor web, and a yieldable joint between said floor web and said lower edge of said interior wall to permit vertical flexing of said floor web in accordance with vertical flexing of said framework truss units to which it is connected, said interior wall having another edge connected to one or more of the truss units of said section, and a yielding joint at said last-named edge to permit vertical movement of the truss unit relative to said edge.
